BEVERAGE DISPENSING HEAD OR SIMILAR ARTICLE

Peter B. Allard, Minnetonka, Minn., assignor to
The Cornelius Company, Anoka, Minn.

Filed Jan. 18, 1972, Ser. No. 218,852

Term of patent 14 years

Int. Cl. D15—08

U.S. Cl. D94—3 B

Fig. 1

Fig. 2

FIG. 3

FIG. 4

FIG. 5

FIG. 1 is a front perspective view of a beverage dispensing head or similar article showing my new design, the mixing valves shown in broken lines being for illustrative purposes only.

FIG. 2 is a rear perspective view thereof.

FIG. 3 is a top plan view thereof.

FIG. 4 is a front elevational view thereof.

FIG. 5 is a side elevational view thereof.

I claim:

The ornamental design for a beverage dispensing head or similar article, substantially as shown and described.
